PLOW CLEVIS.

No. 557,765.

Patented Apr. 7, 1896.

UNITED STATES PATENT OFFICE.

MILTON A. BROWN, OF CLEARFIELD, IOWA.

PLOW-CLEVIS.

SPECIFICATION forming part of Letters Patent No. 557,765, dated April 7, 1896.

Application filed July 15, 1895. Serial No. 555,977. (No model.)

To all whom it may concern:

Be it known that I, MILTON A. BROWN, a citizen of the United States of America, residing at Clearfield, in the county of Taylor 5 and State of Iowa; have invented a new and useful Plow Attachment for Governing the Depth of a Furrow, of which the following is a specification.

My object is to provide a simple and efficient 10 device for raising and lowering the front end of a plow-beam and the point of the plow while the plow is in motion, and I accomplish the results contemplated by my invention constructed and applied and operated as herein- 15 after set forth, pointed out in my claims, and illustrated in the accompanying drawings, in which—

Figure 1 is a side view of a plow and my attachment connected with the plow-beam as required for practical use. Fig. 2 is a bottom 20 view of the front end of the beam and that portion of my attachment connected therewith. Fig. 3 is an enlarged perspective view of mating plates adapted to be fixed to the parallel 25 sides of the front end of the beam to support an adjustable clevis. Fig. 4 is a perspective view showing a modification of my invention by means of which the adjustable clevis can be retained in an elevated position when the 30 draft applied to the clevis, by means of horses hitched thereto, is relaxed.

The letter A designates a plow-beam.

B and B² are metal plates of uniform size and shape adapted to be clamped fast to the 35 sides and front end of a plow-beam by means of bolts, as shown. Their front and wide portions have straight coinciding slots C, that serve as inclined planes for a bolt D, extended through them and also through the ends of a 40 clevis No. 1, that is thus adjustably connected with the plates B and B², that practically constitute a frame.

No. 2 is an auxilliary clevis adjustably connected with the clevis No. 1 for hitching 45 horses thereto.

H is a roller journaled to the plates B and B² in rear of the slots C.

J is a lever fulcrumed to the rear portion of the beam A and connected with the bolt 50 D, that carries the clevis No. 1 up and down in the inclined slots C, that serve as bearings for the movable bolt D. Said connection is

made by means of a chain K, fixed to the bolt D, and a rod L, that is slidingly connected with the under side of the plow-beam and pivotally connected with the lower end of the lever J. 55

M is a rack fixed to the plow-beam, and N is a pawl connected with the lever J to engage the rack as required to retain the lever sta- 60 tionary at any angle desired.

In the modification shown in Fig. 4 the chain K is extended upward from the bolt D and connected with the lever J, above its fulcrum, by means of a rod L², that is slidingly connect- 65 ed with the top of the plow-beam by means of eyebolts or in any suitable way.

In the practical use of my invention the depth of furrow can be readily governed by the lateral adjustment of the clevis No. 2, connected with the clevis No. 1, and the depth of furrow governed, while the plow is in motion, by means of the lever J within reach of the plowman in rear of the plow. To elevate the clevises Nos. 1 and 2, as required to 75 lower the front end of the plow-beam and to increase the depth of furrow, the top end of the lever J is moved rearward, and to produce a reverse action and a furrow of less depth the lever is moved in a reverse way, as 80 required to draw the bolt D down in the inclined slots C.

It is obvious that when a forward draft is applied to the clevis No. 2 the bolt D and the clevis No. 1, carrying the clevis No. 2, will rise 85 to the limit allowed by the chain K, as shown in Fig. 1, and descend by force of gravity when the forward draft is relaxed. It is also obvious that the bolt D can be readily elevated and maintained in an elevated position by means 90 of the lever J and rack M when the bolt is connected with the lever at two points by means of chains and sliding rods, as shown in Fig. 4.

I claim as my invention—

1. A device for regulating the depth of a 95 plow while in motion, consisting of a frame fixed to the front end of a plow-beam and provided with inclined bearings for a bolt, a bolt extended through said bearings, a clevis connected with the ends of the bolt to be carried 100 thereby, a second clevis connected with the clevis on the bolt, a roller journaled in the frame in rear of the inclined bearings, a lever fulcrumed to the rear end of the beam, a rod

pivoted to the lower end of the lever and slid-
ingly connected with the plow-beam, a chain
connected with the rod and extended over the
roller and fastened to the bolt in the inclined
5 bearings of the frame and means for retaining
the lever at various angles relative to the
plow-beam, all arranged and combined with
a plow to operate in the manner set forth.

2. A device for regulating the depth of a
10 plow while in motion, consisting of a frame
fixed to the front end of a plow-beam and pro-
vided with inclined bearings for a bolt, a bolt
extended through said bearings, a clevis con-
nected with the ends of the bolt to be carried
15 thereby, a second clevis, connected with the
clevis on the bolt, a roller journaled in the
frame in rear of the inclined bearings, a lever

fulcrumed to the rear end of the frame, a rod
pivoted to the lower end of the lever and slid-
ingly connected with the plow-beam, a chain 20
connected with the rod and extended over the
roller and fastened to the bolt in the inclined
bearings of the frame and extended upward
and rearward and connected with the lever at
a point above the fulcrum by means of a rod, 25
and means for retaining the lever at various
angles relative to the plow-beam, all arranged
and combined with a plow to operate in the
manner set forth.

MILTON A. BROWN.
